UNITED STATES PATENT OFFICE.

JACOB SIMS, OF BROOKLYN, NEW YORK.

DESIGN FOR A HAND BAG.

Application filed August 3, 1922. Serial No. 3,278. Term of patent 3½ years.

To all whom it may concern:

Be it known that I, JACOB SIMS, a citizen of the United States of America, residing at Brooklyn, in the county of Kings, city and State of New York, have invented a new, original, and ornamental Design for a Hand Bag, of which the following is a specification, reference being had to the drawing forming a part thereof.

Figure 1 is a perspective view of the handbag which is the subject of my invention,

I claim:

The design for a handbag as shown.

JACOB SIMS.
